(57) **CLAIM**

The ornamental design for a door stop, as shown and
described.

DESCRIPTION

Applicant filed a Utility Patent Application having Ser. No.
12/346,418 on Dec. 30, 2008.

FIG. 1 is a front perspective view showing my new design;
FIG. 2 is a right side view thereof;

FIG. 3 is a left side view thereof;

FIG. 4 is a top side view;

FIG. 5 is a bottom side view;

FIG. 6 is a rear end view thereof; and,

FIG. 7 is a front end view thereof.

The broken lines shown in the drawings are for the purpose of
illustrating unclaimed portions of the door stop and form no
part of the claimed design.
